OF MILWAUKEE, WISCONSIN.

EXTENSION-TABLE.

1,170,562.

Specification of Letters Patent. Patented Feb. 8, 1916.

Application filed March 8, 1912. Serial No. 682,508.

To all whom it may concern:

Be it known that we, WILLIAM L. PFEFFERKORN, ALBERT P. SCHLOERB, and AUGUST H. HAMMETTER, citizens of the United States, residing at Milwaukee, county of Milwaukee, and State of Wisconsin, have invented new and useful Improvements in Extension-Tables, of which the following is a specification.

10 Our invention relates to improvements in extension tables.

The object of our invention is to provide improved means for binding the parts of an extension table top rigidly together in any 15 desired position of adjustment. Also to provide means whereby the binding mechanism may be utilized to properly space the several parts of the table so that both ends will open outwardly to the same extent from a 20 common center. Also to provide means whereby the binding mechanism may be utilized to limit the outward movement of the permanent members substantially to the desired degree of extension, whereby when 25 the desired number of removable top boards have been inserted, a comparatively short movement of an operating lever will be sufficient to bring the parts into binding relation with each other.

30 In the drawings—Figure 1 is a plan view of an extension table embodying our invention showing the table in extended position with the removable top boards omitted. Fig. 2 is a view of the same in longitudinal section, drawn on line α — α of Fig. 1. Fig. 3 is a detail view of the binding chain.

Like parts are identified by the same reference characters throughout the several views.

40 In the construction illustrated, fixed top boards 1 and 2 are connected with the end slides 3 and 4 of a series of slides 3, 4, 5 and 6, in the usual manner, the slides and top boards being supported by bridging boards 7 and 8 carried by suitable legs or pedestal members 9 and 10. These parts, as 45 well as the removable top boards, may be of any ordinary construction.

The bridging board 8 in our improved table is provided with a bracket 12 to which a chain 13 is secured at 14, intermediate of its ends but nearer one end than the other. A helically coiled spring 15 is secured to the under side of the top board 2 and is 55 provided with a hook 16 adapted to be en-

gaged by the chain 13. The top board 1 is provided with an elbowed lever 19 pivoted to the under side of the top board at 20 and having a short arm connected with a link 21, having a hooked extremity at 22. A 60 guide at 23 supports the link in substantially a horizontal position. The longer end portion of the chain 13 is adapted to be connected with the hook 22.

When the chain 13 is connected at any 65 points along its length with the hooks 16 and 22, the lever 19 being in the position illustrated in Fig. 1 and the chain being extended as shown in Figs. 1 and 2, it is 70 obvious that by swinging the lever in the direction indicated by the arrow in Fig. 1, the top boards 1 and 2 will be drawn toward each other, since the hook 22 will be drawn inwardly toward the fixed top board 1. If therefore, the space between the top boards 75 1 and 2 be substantially filled with removable top boards prior to the operation of lever 19, the described movement of the lever will bind or clamp such movable top boards between the fixed top boards, and since the 80 chain 13 is connected with the bridging board 8, this will also be drawn in the direction of the bridging board 7 as far as it is permitted to go by the removable top boards, the fixed top boards remaining in 85 the same relative position with reference to the pedestal members. It will be observed, however, that the chain is provided with a series of spaced links a , a , b , b , and c , c ; on the respective sides of the point of connection 14 with the bracket 12. Spaced links d and e are also provided for the longer 90 end portion of the chain 13. The spaces between the links c and d , and d and e , are twice the length of the spaces between the 95 links a and b , and b and c . All of these links are preferably characteristically different either in size, form or appearance from the other links of the chain 13, and are adapted to engage the hooks 16 and 22 100 respectively.

The links a , b and c are separated from each other a distance equal to substantially one-half the width of the top board, but as 105 one of these links is located at each side of the bracket connection 14, it is obvious that each pair of these links represents a separation of the fixed top boards of sufficient dimensions to receive a removable top board, the separation of the fixed top boards being 110

equal on opposite sides of the center of the table between the pedestals. For example, assuming the bridging boards 7 and 8 to be in substantial contact with each other and the fixed top boards 1 and 2 also in substantial contact, if the latter be separated sufficiently to permit the hand of the operator to be inserted between them, the links *a* may be engaged with the hooks 16 and 22 respectively, whereupon a further separation of the top boards 1 and 2 without separating the bridging boards will necessarily involve an equal outward movement of the top boards. A single removable top board may then be inserted and the parts of the table bound together by actuating the lever 19 as above explained. Where two top boards are desired, the operation will be the same, except that the links *b*, *b*, will be engaged with the hooks 16 and 22, while, if three removable top boards are desired, the links *c*, *c*, will be engaged with said hooks. Both of the fixed top boards will then be extended substantially to the limit permitted by the end slides 3 and 4 without separation of the bridging boards, the latter being permitted to remain locked together by a hook 25 pivoted to bridging board 8 and engaging a catch 26 on bridging board 7.

Assuming that it is desired to still further extend the table for the reception of more than three removable top boards, the hook 25 will be released from catch 26 to permit the bridging boards to separate. In this movement of extension, it is not necessary that one end be moved to the same extent as the other end. The chain 13 may therefore be left connected with the hook 16 by means of link *c*, and the other end of the chain connected with hook 22, either by means of links *c* or links *d* for a four or five board extension respectively. These links are separated a distance substantially equal to the full width of a top board for the reason that all the extension is taken care of at this end of the chain. It will of course be understood that the possible extension of the table in this manner is only limited by the capacity of the slides and the number of spaced hook engaging links employed in the chain 13, which may be made of any length to suit the size of the table.

When the table is contracted, the free end or ends of the chain may be permitted to hang. We therefore preferably provide one or both bridging boards with a notch 30, whereby the chain may hang between the bridging boards without interfering with their approach into contact with each other.

By employing links to engage the hooks 16 and 22 which differ from the other links of the chain in appearance, size or form, the user is enabled to adjust the chain without difficulty for any desired extension. The links are preferably engaged with the hooks

immediately after slightly separating the top boards in order that the table may then be extended carelessly until the separating movement is limited by the chain, said chain thus determining the degree of extension. It will of course be understood that the space between the links *a*, *a*, is of a little greater length than the width of a removable top board, so that the separation may be sufficient to allow the top board to be inserted without difficulty, the short arm of the lever 19 being of sufficient length to draw the parts together after the top board is in position and to apply a resilient pressure thereto, the spring 15 being employed to allow the connection made by the chain to yield slightly and compensate for irregularities either in the spacing of the links or in the width of the top boards. It is desirable that the lever 19 be swung through an arc of ninety degrees in order that the link 21 may draw across the line of centers through the pivot pin 20 and the point of connection between the link and said lever. When the lever is so swung, it automatically locks in position with the parts of the table bound together under resilient pressure.

It will be observed that the bridging board 7 is provided with a hook 33 adjustably secured thereto by a bolt 34, which passes through a slot 35 in a plate 36, which carries this hook. The spaced chain links may be engaged with this hook either in addition to the connection with the top board catch, or without making the latter connection. When the chain is engaged with the hook 33, it definitely spaces and limits the separation of the supports represented by the legs, pedestals or bridging boards 7 and 8, and so far as this feature of our invention is concerned, it is not material whether the permanent top boards are movable independently of the supports or not, or whether they are spaced by the same means or not.

We claim—

1. An extension table, comprising the combination of a supporting bridging board, slides, fixed and removable top boards, of a chain connected at one side of its middle portion with the bridging board and provided with suitably spaced catch engaging links of different character from the other links of the chain, catches on the fixed top boards adapted to engage said links, and a lever for adjusting one of the catches to tighten said chain.

2. An extension table comprising the combination with a support, slides, and permanent top boards, of a flexible connecting member secured to one of the top boards and provided with means at spaced intervals along its length, for detachably engaging the other top board.

3. An extension table comprising the com-

bination with a support, slides and permanent top boards, of a flexible connecting member secured to one of the top boards and provided with means at spaced intervals along its length, for detachably engaging the other top board, said flexible connecting member being also secured at one point to the support.

4. An extension table comprising the combination with separable supports, slides, permanent and removable top boards, of a flexible connection secured to one of the supports and provided with means for detachably engaging the other support, at spaced intervals

corresponding substantially to the width of 15 the top boards, and means for allowing an additional separation of the permanent top boards independently of the supports and applying an indrawing tension thereto.

In testimony whereof we affix our signatures in the presence of two witnesses.

WILLIAM L. PFEFFERKORN.
ALBERT P. SCHLOERB.
AUGUST H. HAMMETTER.
